UNITED STATES PATENT OFFICE.

HOWARD E. VAN ORDEN, OF EAST ORANGE, NEW JERSEY, ASSIGNOR OF ONE-HALF TO
JOSEPH W. SINNOTT, OF BROOKLYN, NEW YORK.

TELEPHONE OR OTHER BOOTH.

1,211,790.

Specification of Letters Patent. Patented Jan. 9, 1917.

Application filed March 16, 1915. Serial No. 14,749.

To all whom it may concern:

Be it known that I, HOWARD E. VAN ORDEN, a citizen of the United States, and residing at East Orange, in the county of Essex and State of New Jersey, have invented certain new and useful Improvements in Telephone or other Booths, of which the following is a specification, such as will enable those skilled in the art to 10 which it appertains to make and use the same.

This invention relates to telephone booths, voting booths, and like devices; and the object thereof is to provide a booth of this class composed of separate detachably connected parts and which may be quickly and easily set up for use when and where desired, and also quickly and easily taken down and packed for shipment or other purposes 20 when necessary; and with this and other objects in view the invention consists in a device or devices, of the class specified, constructed as hereinafter described and claimed.

The invention is fully disclosed in the following specification, of which the accompanying drawing forms a part, in which the separate parts of my improvement are designated by suitable reference characters in 30 each of the views, and in which:—

Figure 1 is a vertical section of a booth involving my invention and taken on the line 1—1 of Fig. 2; Fig. 2 a transverse section on the line 2—2 of Fig. 1; Fig. 3 a bottom plan view of the bottom of the booth which is made separately from the body portion of the booth and with which said body portion of the booth is connected; Fig. 4 a perspective inside bottom view of one 40 corner portion of the bottom of the booth; Fig. 5 a view similar to Fig. 2 but showing only one corner portion of the booth but showing said portion on an enlarged scale; Fig. 6 a view similar to Fig. 1 but showing only a part of the bottom portion of the booth and also a part of the body portion connected therewith and on an enlarged scale; Fig. 7 a perspective outside view of one corner part of the body portion of the 50 booth; Fig. 8 a detail sectional view showing a side or back wall of the body of the booth composed of separate parts and showing the method of connecting said parts; Fig. 9 a view similar to Fig. 5 but showing 55 a modification.

In the practice of my invention, I provide a booth of the class specified, comprising a bottom a and a body b composed of separate detachably connected parts and also detachably connected with the bottom a .
60

The booth shown is rectangular in section and the bottom a is rectangular in form and preferably square, and comprises a top portion a^2 having a skirt portion a^3 , and the skirt portion a^3 consists of separate front, back and side portions a^4 having right-angled flange members a^5 on which the top portion a^2 rests and to which said top portion a^2 is secured by welding, brazing or in 65 any other way and, in practice, a sheet a^6 of linoleum or similar material is placed on the top portion a^2 thereof.
70

The skirt portion a^3 , or the front, back and sides thereof are preferably made of a 75 continuous piece of sheet metal bent into the required form and in connection with which the flange members a^5 are formed, and the top a^2 of the bottom a of the booth is also composed of sheet metal, and said bottom of the booth is also braced by transversely arranged brace members a^7 which are secured to the skirt portion a^3 at a^8 by welding, brazing, riveting or otherwise, and one of the brace members a^7 consists of a 80 continuous piece, while the other consists of two pieces secured thereto at a^9 .
85

The body b , in the form of construction shown, consists of a back b^2 , a front b^3 and sides b^4 , and in the construction shown the 90 back and sides consist of single pieces of sheet metal, but in Fig. 8 I have shown a method of making these parts either the side or back, or all of them, of separate pieces which will be hereinafter described.
95

In the construction shown, the front b^3 of the body of the booth is double walled, or consists of parallel sheets b^6 and, in practice, said front b^3 may be provided with a door, or the front b^3 may be omitted altogether, 100 and the front of the booth may be closed by a curtain without departing from the spirit of my invention or sacrificing its advantages. The body of the booth is also provided with a top b^6 below which, when the 105 booth is used as a telephone booth, is a shelf b^7 preferably composed of a bottom sheet b^8 and a top plate b^9 of wood or other fibrous material, or any suitable material may be employed in this connection, and this con- 110

- struction forms between the top b^6 and the shelf b^7 a chamber b^{10} which is normally closed, and in which is placed the usual junction box, circuit wires and other electric apparatus used in connection with the telephone, it being understood that the telephone itself is supported in the usual manner in the body of the booth below the shelf b^7 .
- 10 The sides, back, and front or door member, when said front or door member is employed, are detachably connected, as shown in Fig. 7, in which I have indicated the back b^2 and one side b^4 , and secured to the side b^4 is an angle piece c , and secured to the back b^2 is a strip d having a longitudinal offset portion d^2 , said angle piece c and strip d being composed of sheet metal and being secured to the back and side by welding or in any other way, and the part c^2 of the angle piece c is provided with longitudinal recesses c^3 which open downwardly and outwardly through the edge thereof, and the strip d which is secured to the back b^2 is provided with pins d^3 which are adapted to enter said recesses as indicated in Fig. 7, and in connecting the back and sides, said back is held in proper position and the sides b^4 are manipulated or dropped into position in such manner that the pins d^3 enter the recesses c^3 , and this securely draws and binds the sides and back together.
- 15 It will be observed that the parts c and d are on the inner sides of the sides b^4 and back b^2 , as shown in Fig. 5, and as indicated in Fig. 7, and the offset part d^2 which carries the pins d^3 overlaps the part c^2 of the angle piece c when the sides and back are connected, as herein described, and the outer surface or walls of the booth are smooth and even throughout.
- 20 25 30 35 40

There are angle strips e secured to the sides and back of the body of the booth and to the front when the front is employed, and this connection is preferably made by welding, and when the various parts are connected, as herein described, the angle strips e form a continuous angle strip which extends around the bottom of the body on the inner side thereof and is secured to the bottom a by screws or other suitable devices e^2 , as clearly shown in Fig. 6.

The sides, and back, and the front when said front is employed, are also provided at the top thereof with angle strips f , and the top b^6 of the body of the booth is secured to said angle strips at f^2 by screws, bolts or other suitable devices.

60 The shelf b^7 is also supported by angle strips g secured to the sides of the body of the booth, or to the sides and back, and to the front also, if desired, when said front is employed, and said shelf is connected with said angle pieces by screws or other suitable devices g^2 .

From the foregoing description it will be seen that all the parts of the body of the booth, including the sides, back, and front, when the front is employed, and the top b^6 and shelf b^7 are all detachably connected and the body of the booth is also detachably connected with the bottom a , and by means of this construction all the parts of the booth, as shown in Figs. 1 to 8 inclusive may be quickly and easily set up for use, whenever desired, and as quickly and easily taken down and packed for shipment or other purposes.

In Fig. 8, I have shown one side b^4 of the body of the booth composed of separate plate members b^{11} and connected by strips b^{12} and b^{13} secured to the plate members b^{11} . It will be seen that the strip b^{13} is exactly the same as the strip d shown in Fig. 7, while the strip b^{12} is different from the angle piece c , or consists of a single sheet of metal and the part b^{12} is provided with the slot or slots c^3 the same as in Fig. 7, while the part b^{13} is provided with the pin or pins d^3 . In this way the sides, and the back, may be made up of separate parts and the booth of any desired size may be formed, and the sides and back will be connected in the same manner as shown in Fig. 7, and as hereinbefore described, and this form of construction may also be applied to the front when said front is employed.

In Fig. 9 of the drawing, I have shown a modified construction in which the double walled front b^8 is employed, and in said figure I have shown one of the sides b^4 . In connecting the sides with the front, said front is provided with a channel strip or piece h which is secured therein and welded, or otherwise connected with the opposite walls of said front, and the side b^4 is provided with an angle piece or strip h^2 the same as the strip or angle piece c shown in Fig. 7. In this form of construction, a pin or pins i are employed, the function of which is the same as the pin or pins d^3 , and said pin or pins i are carried by the front b^8 and the channel strip or piece h and, in the form of construction shown, said pin or pins pass through these parts, but this is not absolutely necessary and the said pin or pins i may be secured in the channel strip or piece h only, if desired.

The part h^3 of the angle piece h^2 is provided with the recesses c^3 the same as the angle piece c shown in Fig. 7, and in connecting the side b^4 with the front b^8 said side is manipulated and dropped into position in such manner that the pin or pins i enter the recesses c^3 and securely draw and bind the side b^4 and the front b^8 together.

It will be understood that both sides b^4 are connected with the front b^8 in this manner, and if desired both sides and the back may be composed of double walls and all the

parts of the body of the booth may be connected in the manner shown in Fig. 9.

Having fully described my invention, what I claim as new and desire to secure by

5 Letters Patent, is:—

1. In a knock-down booth, a plurality of side plates provided on their opposite edges and on the inner side thereof with angle plates provided with longitudinal recesses 10 which open outwardly at their lower ends through one edge thereof, and front and back plates provided at their opposite side edges with strips having longitudinal offset portions for overlapping and concealing the recessed portion of said recessed members 15 and provided with pins adapted to enter said recesses.
2. In a knock-down booth of the class described, a wall plate consisting of a plu-

rality of sections, one of said sections being 20 provided with a longitudinally extending strip having longitudinally disposed recesses which open downwardly at their lower ends through one edge of said strip, and the other of said sections being provided 25 with a longitudinal strip having a longitudinal offset portion for overlapping and concealing the recessed portion of said recessed strip and provided with pins adapted to enter said recesses.

In testimony that I claim the foregoing as my invention I have signed my name in presence of the subscribing witnesses this 12th day of March, 1915.

HOWARD E. VAN ORDEN.
